UNITED STATES PATENT OFFICE.

JNO. W. WHITTAL AND WM. W. PENDLETON, OF GREENWICH, CONN.

IMPROVEMENT IN FELT HATS.

Specification forming part of Letters Patent No. 11,462, dated August 1, 1854.

To all whom it may concern:

Be it known that we, JOHN W. WHITTAL and WM. W. PENDLETON, of Greenwich, county of Fairfield, and State of Connecticut, have invented a new and useful Improvement in the Manufacture of Hats; and we do hereby declare that the following is a full, clear, and exact description of the same.

Our invention and improvement consists in the combination of gutta-percha in sheets with manufactured felt cloth, so as to inclose the gutta-percha between two thicknesses of said felt cloth, and afterward forming hats thereof by pressing the said materials into properly-shaped molds while the gutta-percha is in a plastic state, whereby said felt cloth so formed is made to retain the shape thus given to it under all conditions it shall be subjected to in ordinary wear.

We are aware that gutta-percha has been employed as a varnish for hats, but such application is totally different from our use of it, the end accomplished by said use being also quite different. In the use referred to the body of the hat was first fully formed at the blocking-kettle and the gutta-percha, applied as a varnish or stiffener, was simply substitution of one kind of varnish for another—viz., as shellac, &c.—whereas in our invention such use would be of no avail whatever to produce the article we claim to have invented.

Hats formed of felt cloth in sheets by pressure upon a block or in a mold will not retain their form in wet weather, no matter what kind of material is applied as a varnish. We mean by the above such application as will allow the hats to have all the lightness and flexibility of those made in the ordinary way, as anything beyond that would destroy their merchantability, and of course the product would be useless. By our improvements we are enabled to produce from felt in sheets or in the form of cloth, when combined with gutta-percha, also in sheets, hats of superior quality as to use and at a great economy in cost over those manufactured after the old methods.

To make a hat according to our invention

the following plan is pursued: In the first place, a thin sheet of gutta-percha of the proper size to form a hat is covered on both sides with the felt cloth, the cloth being made to adhere by softening the gutta-percha in a manner well known. The felt cloth and gutta-percha thus combined are then softened by steaming or by hot water and laid upon the top of a hollow mold to form the crown. This mold may be either a true cylinder or made oval. If made cylindrical, the hat will require subsequent shaping upon a hatter's block with the aid of a warm iron. A flat board having a hole of the same diameter is laid on, and the pressing-block may be brought down and forced in by the aid of a lever or other appropriate mechanical device. By this means so much of the felt with the gutta-percha between is forced within the mold, the top board meanwhile keeping the rim down flat, and thus the crown is made. The block may now be taken out, and the hat will be fully formed and set solid so soon as the gutta-percha is cold. All that is to be done then to finish the hat is to put in the usual trimmings, bindings, &c. The hat will then be found capable of receiving the roughest possible usage without damage to its shape so long as it is never subjected to a greater degree of heat than 160° Fahrenheit, which it can never get on the head of any wearer. Such hats will be found completely water-proof, very light and flexible, easily conforming to the shape of the head, and be very pleasant to wear.

What we claim as our improvement, and desire to secure by Letters Patent, is—

The formation of hats from felt cloth in sheets combined with gutta-percha, also in sheets, said materials, after being united, to be formed into shape by pressure in a mold or upon a block while the gutta-percha is in a plastic state, as described.

JOHN W. WHITTAL.

WILLIAM W. PENDLETON.
